WEIGHT-GRADING APPARATUS

Bernard Loshak, Boxford, near Colchester,
EnglandApplication April 21, 1938, Serial No. 203,460
In Great Britain April 23, 1937

8 Claims. (Cl. 209—121)

This invention relates to apparatus for sorting or grading articles according to their weight, and particularly to articles such as fruit and vegetables of a globular shape.

5 It is an object of the present invention to provide an apparatus of this kind, comprising a cradle on a horizontally pivoted beam wherein by reason of the preliminary rejection of under-weight articles the grading mechanism can operate with increased rapidity on the articles within the range of weights it is desired to grade.

10 It is another object of the invention to feed an article from the rejecting means to the grading cradle only when the latter is in receiving position by retaining the cradle in that position when empty until it is released therefrom by the weight of an article.

15 It is a further object of the invention to delay the action of the rejecting means to deliver an article above the given weight into the grading cradle when the latter is not in its receiving position.

20 It is a further object of the invention to provide a conveyor for feeding the articles one at a time to the rejecting means, the conveyor being controlled by the latter so that it is operable only when the rejecting means is ready to receive an article.

25 By these various means it is possible to operate a weight grading apparatus of the kind indicated with maximum efficiency.

30 Other objects and advantages of the invention will be apparent from the following description when read in connection with the accompanying drawings, in which—

35 Fig. 1 is a diagrammatic side elevation of one form of complete grading machine;

Fig. 2 is an enlarged view of the cradles and releasing mechanism of Fig. 1;

40 Figs. 3 and 4 are a plan and cross section of one form of feed belt, and

Fig. 5 shows an alternative form of feed mechanism.

45 In order to provide a compact mechanism it is desirable that the beam shall be relatively short, and in this case when there is a considerable number of grades of articles to be separated, it is necessary that the beam shall be capable of swinging through a large angle in order to allow sufficient space for each grade. It is also desirable that the axis of the cradle shall remain substantially vertical throughout its downward swing, so as to prevent an article from falling out of the cradle 50 due to canting of the latter during its swing. This

is effected by providing the beam in the form of a parallel link device, as shown in Fig. 1. In this arrangement the beam comprises a pair of parallel spaced arms 25 and 26 which are pivoted at their ends to two links 27 and 28. The lower end 5 of the arm 25 is fixed on a spindle 29 rotatably mounted in bearings 30 secured to the frame 31 of the machine and the spindle 29 carries a cam 11 to the periphery of which is attached a cord 13 which passes over a guide pulley 17, and carries 10 the control weight 15 on its lower end. The lower end of the upper link 27 extends horizontally towards the front of the mechanism and carries the triangular pyramidal cradle 3 for the articles to be graded, and the other end of the link 27 is 15 slotted or notched at 32 to engage a fixed catch 33 on the frame which retains the cradle 3 when empty in its uppermost position, and a fixed stop 34 is provided to limit the upward swing of the beam and cradle. The upper end of the link 27 20 also carries a projecting arm 35. The lower end of the link 28 pivots on the spindle 29 and has a pin 36 on its other end which passes through a slot in an inclined fixed bracket 37, and a weight 38 is fixed to the link 28 which retains the pin 36 25 at the lower end of its slot and the notch 32 on link 27 in engagement with the catch 33, when the cradle 3 is empty and at the top of its swing.

The cradle 3 is mounted on the lower end of the link 27 and has three outwardly inclined sides or 30 flaps, two of which, 39 and 40, are shown. These sides or flaps are hinged at their lower edge and are retained in their uppermost or closed position by means of catches 41 on the upper end of cranked arms 42 pivotally mounted in brackets 43 35 fixed to the base of the cradle 3. Springs 44, Fig. 2, are provided on the cranked arms 42 to retain them in the position with the catches 41 engaging the side of the cradle flaps, which latter are urged to their closed position, when the cradle is 40 empty, by springs (not shown) on their hinges.

A series of inclined and vertically spaced discharge chutes 45 are mounted adjacent the path of the swing of the cradle 3, and opposite each of its sides (in Fig. 1 only the chutes opposite the 45 side 40 are shown), and each chute 45 carries a bracket 46 to the free end of which is pivoted a finger 47, the outer end of which can swing downwards from the position shown but not upwards, and projects into the path of the swing of the outwardly extending end of the arm 42. The chutes not shown are spaced apart in a similar manner to the chutes 45, but sub-divide the spaces between these chutes 45, so that each chute is disposed at a different level from the others. 55

By employing a cradle which opens on more than one of its sides to discharge the articles as they are graded, it is thus possible to provide a relatively large number of chutes for receiving these graded articles for a given arc of swing of the beam, and this feature, together with the relatively short beam having a parallel linkage, results in an increase in the speed of operation of the apparatus over previously proposed grading machines.

The machine shown in Fig. 1 has a second cradle 48 mounted above the grading cradle 3, the purpose of which is to eliminate articles below a given minimum weight which have been fed to the machine and to deposit the article as lightly as possible into the grading cradle and so prevent the latter from being released by an article under the minimum weight. This cradle 48 is also of triangular shape with its rear side 49 pivoted at 50 to one end of a beam 51, and the other two sides 52 (one only of which is shown) are hinged together along their lower edges, the hinge 53 being secured at one end to the lower corner of the side 49, and the sides 52 are urged to their uppermost or closed position by means of a spring (not shown) on the hinge 53, when the cradle 48 is empty.

The beam 51 is mounted at 54 to swing vertically in a bearing fixed to the frame 31 of the machine, and has a counterweight 55 adjustably mounted on its end opposite to the cradle 48, so that when the cradle 48 is empty the beam rests in its uppermost position against a fixed stop 56 on the frame.

The cradle 48 is normally prevented from swinging about the pivot 50 and held in its uppermost position relative to the beam 51, by means of a trigger 57 pivoted to the beam 51, with its upper end arranged to engage a catch 58 on the back 49 of the cradle, a stop 60, Fig. 2, being provided to retain the trigger 57 in a position so that it can re-engage the catch 58 after it has been released. A catch 61 is fixed on the underside of the beam 51 adjacent the pivot 50, and is arranged to engage a spring trigger 62 mounted on an arm on the frame 31 when the beam is at the bottom of its swing; and the trigger 62 is provided with a rearwardly projecting finger 63.

The sides 52 of the cradle 48 are retained in their closed position by means of catches 64 pivoted on the upper corners of the back 49, and their rearwardly projecting ends are arranged to engage pivoted fingers 65 on the frame similar to the fingers 47 when the cradle 48 swings vertically, so that the sides 52 are released to swing outwardly owing to the weight of an article in the cradle 48 only during the upward swing of the latter. Also discharge chutes 66 are provided at each side of the path of swing of the cradle 48 for receiving the underweight articles discharged therefrom. The chute 66 and corresponding releasing fingers 65 on one side of the cradle 48 may be disposed at a different level from those on the opposite side so that underweight articles within two different limits of weight may be separated from each other.

The feeding mechanism in the apparatus illustrated in Fig. 1 consists of an endless belt 67 mounted on rollers or pulleys 68 and driven in the direction of the arrow by any suitable means. The outer surface of the belt 67 is curved as shown in Fig. 4 and has depressions 69 spaced along its length which are just suf-

ficiently large to retain a single article to be graded.

The articles are fed to the machine by means of an endless belt conveyor 70 from which they pass down an inclined guide chute 71, on to the belt 67; only one article can remain in each depression, and the others roll off and fall on to travelling belts 72 on each side of the belt 67 and are returned to the point from which they are fed on to the conveyor 70.

As the belt 67 moves forward the articles fall from the depressions 69 into the cradle 48 which then swings downward. The speed of the belt 67 is regulated so that the rate at which the articles are fed to the cradle 48 does not exceed the time of a downward and return swing of the cradle.

If the article in the cradle 48 is equal to or above the given minimum weight to be graded, the cradle with the beam 51 will swing down to the full extent of its travel, and if the grading cradle is in its uppermost position as shown in Fig. 1, the spring trigger 62 will be pushed back by the finger 35, so that the trigger 62 does not engage the catch 61, but the finger 63 on the trigger will engage the lower end of the trigger 57 and release it from the catch 58, thus allowing the cradle to tip forward and deposit the article into the grading cradle 3, after which the cradle 48 and beam 51 swing back to their uppermost position, and as the beam 51 strikes the stop 56, the empty cradle 48 tips up due to its momentum, so that the trigger 57 re-engages the catch 58 and retains the cradle 48 in position ready to receive another article.

As the cradle 48 swings downwards the catches 64 contact with the fingers 65 and cause the latter to turn about their pivots without releasing the catches 64. However, if the article deposited in the cradle 48 is below the given minimum weight, the latter will swing down through an angle smaller than the full extent of the swing, thus failing to discharge the article from the cradle and as it swings back the catch 64 engages the finger 65 which, since it cannot move upwards, causes the catch 64 to turn and release the cradle side 52, which then swings outwards due to the weight of the article, which latter is then discharged into the chute 66; whereupon the side swings back to its closed position due to the spring on the hinge 53, and the cradle returns to its uppermost position.

If the grading cradle 3 is not in position at the top of its swing when the cradle 48 reaches its lowest point, the latter cradle will be retained in this position by the catch 61 which engages the spring trigger 62 and the finger 63 will not contact the trigger 57 and when the cradle 3 returns to the top of its swing the finger 35 releases the spring trigger 62 from the catch 61 and causes the finger 63 to release the trigger 57 from the catch 58, so that the article is discharged from the cradle 48 and the latter swings back as described above.

As soon as an article is deposited into the grading cradle 3, the link 27 pivots on the upper end of the arm 25, thus releasing the catch 33 and causing the pin 38 to move to the upper end of its slot in the bracket 37, the weight 38 being adjusted so that the lightest article to be graded will release the catch 33 when placed in the grading cradle 3.

The cradle 3 then swings downwards and the extent of this swing is the greater according as the weight of the article in the cradle is greater,

and during this downward swing the cord 13 wraps round the curved periphery of the cam 11 so that the leverage of the balance weight 15 is increased as the extent of the swing increases, 5 and the contour of the cam is of such a shape that the beam and grading cradle 3 swing through substantially equal angles for each equal increment of weight added to the grading cradle.

As the grading cradle descends the projecting 10 ends of the cranked arms 42 depress each of the fingers 47 in turn as they swing past, without releasing the catches 41. When the cradle commences its return swing one of the projecting 15 arms 42 contacts the underside of the lowest finger 47 which it has just passed, and since this latter finger cannot move up, the projecting arm 42 is pressed down thus releasing the catch 41, so that the corresponding side of the cradle swings out on its hinge under the weight of the 20 article, which latter is discharged into the corresponding chute 45, and the cradle side swings back into its closed position, the outer face of the catch 41 being bevelled to allow the cradle 25 flap to move past, after which the cradle 3 swings back to its uppermost position and is retained by the catch 33 ready to receive another article.

The feeding mechanism shown in Fig. 5 consists of an endless belt 73 mounted on pulleys or 30 rollers 74 which are free to rotate in the fixed frame 31 of the machine. Attached to the outer surface of the belt 73 throughout its length is a series of spaced shallow cups 75 which are just 35 sufficiently large to hold a single article to be graded; also projecting from one side of the belt 40 is a series of pins 76 spaced apart at a distance equal to the spacing of the cups 75. An approximately Z-shaped member is pivoted at about its centre to an arm of the frame 31 and is urged by a spring 78 so that its downwardly directed arm 45 contacts the beam 51, when the latter rests against the stop 56, and so that its upwardly directed arm 77 extends into the path of travel of the pins 76.

The articles are fed into the cups 75 on the 45 upper sloping run of the belt 73, and travel down by their own weight towards the cradle 48 into which they are discharged. When this cradle 48 is in its uppermost position, as shown, the beam 51 presses up the left hand arm of the member 50 77 so that its right hand arm is moved out of the path of the pins 76 to allow the belt 73 to rotate. When an article is deposited in the cradle 48 and the beam 51 moves down, the member 77 turns about its pivot so that its right hand end comes 55 into the path of the pins 76, thus preventing further feeding movement of the belt until it is again released when the beam 51 returns to the top of its swing.

If desired the upper cradle 48 may be omitted 60 from the machine so that the articles will be fed directly into the grading cradle 3, in which case, if the feeding mechanism shown in Fig. 5 is employed, means may be provided on the parallel link beam for operating the feed release member 65 77.

Also, if desired, the cradle may be of other than 70 triangular cross-section and one or more of its sides may be formed as hinged flaps as described, the remainder being fixed, in which case it is only necessary to provide discharge chutes opposite the sides which are arranged to open.

What I claim is:

1. Apparatus for grading articles according to weight, comprising in combination a beam pivoted at one end on a fixed horizontal axis,

a grading cradle on the other end of the beam, a balance weight so connected to the pivoted end of the beam that the leverage of said weight is progressively increased as the extent of the downward swing of the beam is increased, means 5 whereby an article is released from the grading cradle adjacent the bottom of its swing, means such as a second pivoted beam and cradle disposed above the grading cradle and adapted at the bottom of its swing to deposit an article 10 above a given weight into the grading cradle and to reject an article below the given weight on its return swing, a catch associated with the first named beam whereby the grading cradle is retained in its top position when empty, and 15 is released therefrom by the weight of an article in said grading cradle, and a further catch associated with the second cradle whereby said second cradle, when loaded with an article above the given weight, is retained at the bottom of 20 its swing when the grading cradle is not in its top position.

2. Apparatus for grading articles according to weight, comprising in combination a beam pivoted at one end on a fixed horizontal axis, a 25 grading cradle on the other end of the beam, a balance weight so connected to the pivoted end of the beam that the leverage of said weight is progressively increased as the extent of the downward swing of the beam is increased, means 30 whereby an article is released from the grading cradle adjacent the bottom of its swing, means such as a second pivoted beam and cradle disposed above the grading cradle and adapted to deposit an article above a given weight into the 35 grading cradle at the bottom of its swing and to reject an article below the given weight on its return swing, an endless conveyor disposed above the second cradle, whereby articles to be graded are fed singly to the second cradle, and feed 40 control means operated by the second named beam, whereby the feed conveyor is operable only when the second cradle is in its top position.

3. Apparatus for grading articles according to 45 weight comprising in combination a beam pivoted on a fixed horizontal axis, a grading cradle on the beam, means for varying the downward swing of the beam according to the weight of an article loaded into the cradle, rejecting means 50 adapted to deposit an article above a given weight into the grading cradle and to reject an article below the given weight, means whereby an article is released from the grading cradle adjacent the bottom of its swing, and means whereby the said 55 grading cradle is retained in its receiving position when empty and is released therefrom by the weight of an article in the said grading cradle.

4. Apparatus for grading articles according to weight comprising in combination a beam pivoted on a fixed horizontal axis, a grading cradle on the beam, means for varying the downward swing of the beam according to the weight of an article loaded into the cradle, rejecting means adapted to deposit an article above a given weight 65 into the grading cradle and to reject an article below the given weight, means whereby an article is released from the grading cradle adjacent the bottom of its swing, means whereby the said grading cradle is retained in its receiving position 70 when empty and is released therefrom by the weight of an article in the said grading cradle, and means whereby the action of the rejecting means to deliver an article above the given weight into the said grading cradle is delayed 75

when the said grading cradle is not in its receiving position.

5. Apparatus for grading articles according to weight comprising in combination a beam pivoted on a fixed horizontal axis, a grading cradle on the beam, means for varying the downward swing of the beam according to the weight of an article loaded into the cradle, rejecting means adapted to deposit an article above a given weight into the grading cradle and to reject an article below the given weight, means whereby an article is released from the grading cradle adjacent the bottom of its swing, a conveyor whereby articles to be graded are fed singly to the rejecting means, and feed control means operated by the rejecting means whereby the conveyor is operable only when the rejecting means is ready to receive an article.

6. Apparatus for grading articles according to weight, comprising in combination a beam pivoted at one end on a fixed horizontal axis, a grading cradle on the other end of the beam, a balance weight so connected to the pivoted end of the beam that the leverage of said weight is progressively increased as the extent of the downward swing of the beam is increased, means whereby an article is released from the grading cradle adjacent the bottom of its swing, rejecting means including a second pivoted beam and cradle disposed above the grading cradle and adapted at the bottom of its swing to deposit an article above a given weight into the grading cradle and to reject an article below the given weight on its return swing, a catch associated with the first named beam whereby the grading cradle is retained in its top position when empty and is released therefrom by the weight of an article in said grading cradle and a further catch associated with the second cradle whereby said second cradle, when loaded with an article above the given weight, is retained at the bottom of its

swing when the grading cradle is not in its top position.

7. Apparatus for grading articles according to weight, comprising in combination a beam pivoted at one end on a fixed horizontal axis, a grading cradle on the other end of the beam, a balance weight so connected to the pivoted end of the beam that the leverage of said weight is progressively increased as the extent of the downward swing of the beam is increased, means whereby an article is released from the grading cradle adjacent the bottom of its swing, rejecting means including a second pivoted beam and cradle disposed above the grading cradle and adapted at the bottom of its swing to deposit an article above a given weight into the grading cradle and to reject an article below the given weight on its return swing, an endless conveyor disposed above the second cradle whereby articles to be graded are fed singly to the second cradle, and feed control means operated by the second named beam whereby the feed conveyor is operable only when the second cradle is in its top position.

8. Apparatus for grading articles according to weight, comprising in combination a beam pivoted on a fixed horizontal axis, a grading cradle on the beam, means for varying the downward swing of the beam according to the weight of an article loaded into the cradle, rejecting means adapted to deposit an article above a given weight into the grading cradle and to reject an article below the given weight, means whereby an article is released from the grading cradle adjacent the bottom of its swing, a retaining latch operative to hold the cradle in its receiving position as long as the cradle is empty, and means actuated by the article being deposited into said cradle for releasing said latch to permit said beam to be depressed in accordance with the weight of the article to be graded.

BERNARD LOSHAK.
